UNITED STATES PATENT OFFICE.

MARY HANNAH CLARKE, BORN ASHTON, AND DEMETRIO MAGGIORA, OF PARIS, FRANCE.

BOMB-LAUNCHING APPARATUS.

1,262,609.

Specification of Letters Patent.

Patented Apr. 9, 1918.

Application filed November 5, 1915. Serial No. 59,817.

To all whom it may concern:

Be it known that we, MARY HANNAH CLARKE, born ASHTON, married woman, of 10 Rue du 4 Septembre at Paris, Republic 5 of France, British subject, banker, and DEMETRIO MAGGIORA, engineer, Italian subject, of 10 Rue du 4 Septembre at Paris, Republic of France, have invented certain new and useful Improvements in Bomb-10 Launching Apparatus; and we do hereby declare the following to be a full, clear, and exact description of the invention, such as will enable others skilled in the art to which it appertains to make and use the same.

15 The present invention relates to an apparatus for launching a bomb by the explosion of a gaseous mixture.

This apparatus is composed of an explosion chamber provided with a cylindrical tube or barrel containing the bomb. The gaseous mixture, which is preferably acetylene gas, is introduced into the explosion chamber by means of a conduit, the ignition being effected by an automatic lighter or 20 like device. The pressure of the gases at the moment of the explosion, expels the projectile with great force and admission valves subsequently permit of the re-admission of air and the exhaust of the burnt gases.

25 30 The accompanying drawings illustrate, by way of example, a constructional form of the invention.

Figure 1 is a side elevation of the bomb launching apparatus in a vertical plane.

35 Fig. 2 is a vertical section.

Fig. 3 is an end view.

Fig. 4 is a vertical section through a modification.

Fig. 5 is an enlarged detail showing the 40 three-way valve in one of its positions.

Referring to Figs. 1 and 2, 1 is the cylindrical wall of the explosion chamber, which is provided with two ends 2 and 3. The barrel 4 of the weapon, is secured to the end 2 45 and receives a projectile such as a bomb, grenade or the like. The explosive mixture is introduced through a perforated conduit 6 and supplied from the exterior through a pipe 7, which latter is divided into two 50 branches 7¹ and 7² as clearly illustrated. A three way valve 8 places the pipe 7 in communication with conduits 7¹ and 7² or places the latter in communication with each other,

shutting off the pipe 7 at the same time. It is thereby possible to communicate with a 55 generator through the pipe 7¹ and with a measuring device M through the pipe 7² or place the generator in communication with the measuring device. Instead of the valve and of the measuring device, use may be 60 made of any kind of measuring device. The two ends 2 and 3 are connected to each other by means of stays 9 provided with bolts 10 at their ends. The ends of the chamber 1 are, moreover, perforated at 11 (see Fig. 3) 65 for the reception of air admission valves. The valves comprise a plate 12, provided with a rod 13 and a spring 14, abutting against a nut of the rod 13 and a ring 15 fitted into the end 2. These valves are provided upon both ends 2 and 3 and in alignment in order to aerate completely the interior of the explosion chamber and give rise to ventilating currents parallel to the 70 axis of the apparatus.

75 The opening of the valves may be effected simultaneously through the medium of a system of rings and levers shown in Fig. 1.

The illustrated controlling system is composed of two rings 16 and 16¹, pivoted at 17 80 and 17¹, respectively, upon arms connected with the cylinder 1. These rings are, furthermore, interconnected by means of a rod 18, a lever 19 pivoted to the arm 20, integral with the cylinder 1, and a link 21, so that 85 when the rod 18 is displaced to the left, the system assumes the position indicated in dotted lines (Fig. 1) causing the rings to bear on the tail ends of the valves and thereby opening the latter. The cylinder 1 is extended by a sectional cylinder 22 which 90 serves as a support for the apparatus and is secured by means of a rod 23 and a hinged connection 24 to a board 25 which may be securely placed on the soil of the trench.

95 Fig. 4 illustrates a modification in which the barrel 4 is located in the interior of the explosion chamber. In this construction the gases penetrate the tube 4 through perforations 26 formed at the end thereof nearest 100 to the end 3. This constructional form of the apparatus decreases the volume occupied by the apparatus and facilitates the transport of the latter.

105 The conduit 6 may then be constituted by a series of rings 6¹, 6², 6³ and 6⁴ concentric

with the tube 4 for the purpose of insuring a uniform distribution of the gaseous mixture in the explosion chamber.

Claims:

- 5 1. An apparatus for launching bombs, comprising an explosion chamber, a reduced tube or barrel associated therewith, and air inlet relief valves positioned in both ends of said explosion chamber.
  - 10 2. An apparatus for launching bombs, comprising an explosion chamber, a reduced tube or barrel connected to one end of said explosion chamber, and positively operated air inlet relief valves associated with both ends of said explosion chamber, said valves so arranged as to create, when open, a passage of air through the explosion chamber parallel to the axis of said chamber.
  - 15 3. An apparatus for launching bombs, comprising a relatively large cylindrical explosion chamber, a smaller cylindrical chamber comprising a firing chamber wholly within the explosion chamber and surrounded thereby, and a series of perforated annular conduits uniformly distributed throughout the explosion chamber and encircling the firing chamber for supplying the necessary explosive gaseous mixture to said explosion chamber.
  - 20 4. An apparatus for launching bombs, comprising a relatively large cylindrical explosion chamber, a smaller cylindrical chamber comprising a firing chamber wholly within the explosion chamber and surrounded thereby, a series of perforated annular conduits uniformly distributed throughout the explosion chamber and encircling the firing chamber for supplying
  - 25
  - 30
  - 35
- the necessary explosive gaseous mixture to said explosion chamber, and air inlet relief or exhaust valves positioned in both ends of said explosion chamber.
5. An apparatus for launching bombs comprising an explosion chamber, a barrel connected therewith, a gas supply conduit, a conduit adapted to be connected to a measuring device and communicating with the supply conduit, a conduit common to both of the aforementioned conduits and communicating with the explosion chamber, and means for establishing communication, selectively, between the supply conduit and the common conduit or the supply conduit and the measuring conduit.
6. An apparatus for launching bombs comprising an explosion chamber, a barrel connected therewith, means for opening both ends of the explosion chamber, and means common to both of the aforementioned means for operating the same.
7. Apparatus for launching bombs comprising a cylindrical explosion chamber, a barrel connected therewith, said explosion chamber having a series of openings in each end arranged concentrically therewith, means for normally closing said openings, and means for operating all of said aforementioned means simultaneously to uncover said openings.

In testimony whereof we affix our signatures, in presence of two witnesses.

MARY HANNAH CLARKE, BORN ASHTON.

DEMETRIO MAGGIORA.
